RADIO TUBE

Earl C. Handschug, St. Louis, Mo.

Application January 23, 1935, Serial No. 3,063

7 Claims. (CL. 250—27.5)

This invention relates to an improvement in radio tubes and the like.

The object of this invention is to provide simple and effective means for identifying a new tube, the means being such that, while permitting the tube to be tested, it must be removed before the tube can be used in a socket for which it is adapted.

Fig. 1 is a side view of a tube embodying the invention;

Fig. 2 is an end view;

Fig. 3 is a side view of another embodiment of the invention; and

Fig. 4 is an end view of the modification shown in Fig. 3.

In the embodiment shown in the attached drawing the identification comprises a post or pin which is integrally attached to the tube by a slender section of material. The arrangement is such that if the pin is bent the connecting portion of metal will break. The identifying pin or post is so arranged as to permit testing of the tube in a properly constructed apparatus, but such as to prevent the insertion of the tube in a regular socket for which it is intended. As shown in the embodiment of Figs. 1 and 2 the identifying pin may be an extension of a contact prong or, as shown in the embodiment of Figs. 3 and 4, it may be a separate device secured in the base of the tube.

The essential features of the invention are pointed out in the appended claims, and the following detail description of the structure shown in the accompanying drawing will assist in understanding the invention.

A bulb 1 of a radio tube, or the like, is carried on and secured in a base 2. The filament and appurtenant parts within the bulb, and which are not shown in the drawing, are connected in a conventional manner to a plurality of contact prongs 3, four of which are shown.

In the embodiment shown in Figs. 1 and 2, one of these prongs has an elongated portion 4 connected by a reduced portion of metal 5. Thus the contacts are all exposed and the tube may be tested but the prongs cannot be inserted in a socket adapted to receive the tube until the portion 4 has been removed by breaking the metal at the space shown at 5.

When the portion 4 has been broken it will indicate a used tube, and thus the projecting element will identify a new device.

The projecting portion 4 may be in line with the prongs 3 to which it is attached, or it may be bent sidewise, as shown in the drawing. It is

preferable to bend it sidewise because in such case the extended portion 4 will readily break off if an attempt is made to insert the tube in a socket.

In the embodiment shown in Figs. 3 and 4, the identifying pin or post comprises a separate element 6 rigidly secured in the base 2 and has an extended portion 7 connected with the other portions by a reduced section 8. The element 6 may not be made of metal but may be made of any selected material since it has no function to perform except that of identification. It thus differs from the embodiment shown in Figs. 1 and 2, because in that embodiment the element 4 as well as the post 3 to which it is attached must be conductive and thus of metallic material.

The element 6 may be extended downwardly from the base, as shown, or it may be otherwise positioned where the extended portion 7 will interfere with an appropriate socket, depending upon the type of tube and type of socket used. The extension 7 may be in line with the remaining portion of the element or it may be angular thereto, as explained in connection with the other embodiment.

The reduced sections 5 and 8 in the respective embodiments are such that they may be broken by manual manipulation of the extended or identifying portions.

It will be obvious from the foregoing description that applicant has provided a device which is simple in construction, and which will serve to identify a new tube. This must be true because the identifying portion must be broken off in order to insert the tube in a socket for which it is adapted.

I claim:

1. In combination with a tube having a base adapted to cooperate with a socket for connection with an electrical circuit, a member rigidly secured to said base and having a projection integral therewith, so arranged as to prevent the insertion of the base in cooperative relationship with said socket while such projection is attached and to permit such insertion after the projection is removed, such projection being connected with the remaining portion of the member by a reduced portion of the material of which it is constructed to facilitate the projection being broken off at the reduced portion.

2. In combination with a tube having a base adapted to cooperate with a socket for connection with an electrical circuit, a member rigidly secured to said base and having a projection in-

tegral therewith, so arranged as to prevent the insertion of the base in cooperative relationship with said socket while such projection is attached and to permit such insertion after the projection is removed, such projection being connected to the remaining portion of the member by a reduced portion of the material of which it is constructed so as to permit the projection being broken off readily at the reduced portion by manual manipulation of the projection.

3. In combination with a tube having a base and a plurality of metallic contact prongs rigidly secured to the base, a projection on one of the prongs integral therewith and connected thereto by a reduced portion, constructed and arranged whereby such projection while attached prevents the insertion of said prongs in sockets for which they are adapted and permits such insertion when the projection is broken off at the reduced portion.

4. In combination with a tube having a base and a plurality of metallic contact prongs rigidly secured to the base, a projection on one of the prongs integral therewith and connected thereto by a reduced portion disposed angularly to such prong, and constructed and arranged whereby such projection while attached prevents the insertion of said prongs in sockets for which they are adapted and permits such insertion

when such projection is broken off at the reduced portion.

5. In combination with a tube having a base and a rigid metallic contact member secured to the base and adapted to cooperate in and with a socket for electrical connection, a projection on said contact member positioned to prevent the insertion of said member in such socket and integrally connected with said member by a reduced portion of the metal so constructed and arranged to permit the projection being broken off readily at the reduced portion by manual manipulation.

6. In a device of the kind described including a base having a plug adapted to be received in a socket to make electrical contact, a frangible projection secured to the base and preventing the plug from entering the socket, said element preventing use of the device in the socket until it is broken off.

7. In a device of the kind described including a base having a plug adapted to be received in a socket to make electrical contact, a removable projection secured to the base and preventing the plug from entering the socket until removed, the projection not interfering with the electrical conductivity of the plug, whereby the device may be tested while the projection is on the base.

EARL C. HANDSCHUG.
